FIG. 1.

FIG. 2.

FIG. 3.

FIG. 4.

FIG. 5.

Inventor

Edmond DeGrace

By Clarence A. O'Brien
Attorney

UNITED STATES PATENT OFFICE

EDMOND DE GRACE, OF DETROIT, MICHIGAN

RAILROAD-TRACK JOINT

Application filed April 15, 1930. Serial No. 444,474.

This invention appertains to a new and useful improvement in railroad surface trackage, and more particularly to a novel joint structure, whereby track sections are connected together.

An important object of the invention is to provide a track so constructed as to eliminate the usual jar of the rolling stock passing thereover.

During the course of the following specification and claims, other important objects and advantages of the invention will readily become apparent to the reader.

In the drawings:—

Figure 1 represents a fragmentary top plan view of the novel rail joint.

Fig. 2 represents a longitudinal sectional view through the rail joint, taken substantially on the line 2—2 of Fig. 1.

Fig. 3 is an enlarged cross sectional view taken substantially on the line 3—3 of Fig. 1.

Fig. 4 represents a perspective view of the block insert.

Fig. 5 represents a perspective view of the block retaining element.

Referring to the drawings, wherein like numerals designate like parts, it can be seen that numeral 5—5 represents the track sections provided with the usual tread portions 6 and base plates 7. The abutting end portions of the rails are thickened as at 8 to substantially the width of the tread portion 6.

As is clearly shown in Fig. 1, each end of each rail 5 is cut inwardly as at 9, obliquely as at 10 and then backwardly on a plane parallel to the cut 9, as is shown at 11.

For interposition between adjacent ends of the rails 5—5, a block generally referred to by numeral 12 is provided. This block is of rectangular shape and beveled on one side thereof from its intermediate portion 13 toward each end as at 14. These beveled portions 14 are adapted to engage against the obliquely disposed portions 10 of the rail ends, while the shoulders 15 engage the portions 11 of the rail ends.

The ends of the blocks engage against the portions 9 on the rail ends. As is clearly shown in Fig. 4, the block 12 is provided with an opening 16, extending therethrough for

receiving the polygonal pin 17. The pin 17 is provided with a wedge-shaped head 18 at one end, and a threaded reduced portion 19 at its opposite end.

The pin 17 adjacent the reduced portion 19 is beveled as at 20. A rail chair 21 is employed in conjunction with the joint, and has the usual upstanding flanges 22, 22. Through these flanges, openings 23, are provided which have beveled faces against which the wedge-shaped head 18 and beveled surface 20 may engage for wedging the pin so as to direct the block 12, downwardly to maintain the same always snugly seated within the chair.

The rail ends 8 are also similarly provided with openings, through which other pins 17 extend to maintain the ends of the rails snugly seated within the chair.

Obviously, it can be seen that rolling stock passing over the joints will ride thereover evenly and without jarring. While the foregoing specification sets forth the invention in detail, it is to be understood that numerous changes in the shape, size and materials may be restored to without departing from the spirit and scope of the invention as claimed hereinafter.

Having thus described my invention, what I claim as new is:—

1. In a railroad track joint, a pair of rail sections disposed in end to end relationship and having a pair of spaced adjacent ends, said ends being of equal transverse thickness throughout their height and having their terminals beveled laterally so that faces formed by the terminals converge toward each other in one direction, a rail chair in which said ends are positioned, and a beveled insert block of equal thickness with said ends and positioned between the ends with faces abutting the terminal spaces of the said ends.

2. In a railroad track joint, a pair of rail sections disposed in end to end relationship and having a pair of spaced adjacent ends, said ends being of equal transverse thickness throughout their height and having their terminals beveled laterally so that faces formed by the terminals converge toward each other in one direction, a rail chair in which said ends are positioned, and a beveled in-

sert block of equal thickness with said ends and positioned between the ends with faces abutting the terminal faces of the said ends, said abutting faces being formed with abutting shoulders adjacent the sides of the rail ends.

In testimony whereof I affix my signature.
EDMOND DE GRACE.
